UNITED STATES PATENT OFFICE.

FRANK C. LEWIS, OF MILWAUKEE, WISCONSIN.

PUMP.

SPECIFICATION forming part of Letters Patent No. 743,299, dated November 3, 1903.

Application filed January 9, 1903. Serial No. 138,336. (No model.)

To all whom it may concern:

Be it known that I, FRANK C. LEWIS, a citizen of the United States, and a resident of Milwaukee, in the county of Milwaukee and State of Wisconsin, have invented certain new and useful Improvements in Pumps; and I do hereby declare that the following is a full, clear, and exact description thereof.

My invention has for its object to provide a pump which is especially designed for use in retailing vinegar direct from the barrel into the consumer's vessel, the quantity being measured in a dome in said pump, thereby doing away with the several measures required ordinarily, which for sanitary reasons as well as a saving of time is greatly to be desired; and it consists in certain peculiarities of construction and combination of parts, to be fully set forth hereinafter with reference to the accompanying drawings, and subsequently claimed.

The drawing illustrates an elevation of my improved pump, with parts broken away and in section, so as to best show the invention, a portion of the barrel being broken out for convenience.

Referring by letters to the drawing, A is a barrel, which is preferably made of wood, so as not to be affected by acid, and is of such length and diameter that it may be readily inserted into a cask through its bung, its lower end resting upon the bottom of said cask, with the discharge-spigot B a sufficient distance above the head of the latter so as to admit of a vessel being placed thereunder.

The barrel A at its lower end is provided with recesses a, through which the liquid passes, and C is a hollow plug fitted into said barrel above the recesses to form a seat for a ball D of glass or other non-corrodible material.

A pump-rod E, of wood, has at its lower end a cage F of the same material fitted thereto, the bottom portion b of which has an annular groove c, that is wound with string to form a sucker for the pump. Said portion b is also provided with a central recess d, that is normally closed by a glass ball e, confined within the cage F.

The barrel A terminates with a square head G, into the central bore of which is detachably fitted the neck of a transparent dome

H, this dome having its top slightly concaved, with a central opening f larger in diameter than the pump-rod E, which passes therethrough and terminates with a suitable handle.

Close to the neck of the dome H and communicating therewith is the wooden spigot B, which is driven into the head G, as shown.

It is obvious that when the pump-rod is reciprocated on its upward stroke it will lift the ball D from its seat and draw in a charge of liquid, and when reversed said ball will close the hollow plug C, this causing the ball e in the cage F of the pump-rod to lift and allow the liquid to pass through the cage, where it is retained above the sucker, this operation being repeated until the pump has filled the dome or the desired amount has been raised therein, it being in plain sight of the operator, owing to the transparency of said dome. The spigot is then opened and the amount in sight drawn off.

By reason of the detachable dome H when it is desired to clean the several parts of the pump it may be readily done by simply lifting said dome, together with the pump-rod, from the barrel A, thus giving access to the entire device.

In case it is desired to fill the dome it is necessary to prevent an air-cushion at its top, and for this reason, as previously described, I make the opening f larger than the pump-rod, so that the air may escape, and should the liquid slightly overflow it would be caught in the concave top and drain back into the dome when the discharge-spigot is opened.

It is obvious that any size dome may be used, or, as shown, I may use one large enough for all purposes and provide the same with graduation-marks to indicate various quantities usually sold.

Having thus described my invention, what I claim as new, and desire to secure by Letters Patent, is—

1. In a pump, a pump-barrel, a transparent dome detachably fitted into the head of the barrel, openings at either end of said dome, a pump-rod adapted to be reciprocated through said openings and of less diameter than the latter, a suction-valve at the lower end of the pump-rod, a check-valve located at the bot-

tom of the pump-barrel and a spigot in communication with the lower opening of the dome, substantially as set forth.

2. In a pump, a pump-barrel, a transparent dome having a hollow neck fitted into the head of the barrel, said dome being provided with a concave top having a central opening therein, a pump-rod adapted to be reciprocated through the dome and provided with a suction-valve at its lower end, a check-valve located at the bottom of the pump-bar-

rel, and a spigot in communication with the neck of the dome, substantially as set forth.

In testimony that I claim the foregoing I have hereunto set my hand, at Milwaukee, in the county of Milwaukee and State of Wisconsin, in the presence of two witnesses.

FRANK C. LEWIS.
